UNITED STATES PATENT OFFICE.

MAX R. LEHMAN, OF QUINCY, ILLINOIS, ASSIGNOR TO ORBON STOVE CO., OF BELLEVILLE, ILLINOIS, A CORPORATION OF DELAWARE.

STOVE TOP.

Application filed February 13, 1928. Serial No. 252,903.

This invention relates to stove tops, and has special reference to stove tops having pivotal connection with the stove and surmounted by urn bases also having pivotal connection with the stove, and means for operating the urn base by the top.

An object of the invention is to provide a stove top having pivotal connection with the upper end of a stove for horizontal swinging movements to open and to closed position, in combination with an urn base having pivotal connection with the stove, and means for operating the urn base by the stove top so that the urn base is mounted at all times in proper relationship to the top.

Another object of the invention is to provide a stove top and urn base having independent pivotal connection with the stove and having slight connection with each other whereby the stove top will operate the urn base while most of the weight of the urn base is sustained by the stove instead of by the top.

Other objects will appear from the following description, reference being made to the accompanying drawing in which

Fig. 1 is a front elevation of my improved stove top and urn base mounted upon the upper end of a stove.

Fig. 2 is a plan view of the invention showing the stove top in closed position and the urn base turned around to open position, and showing in broken lines the positions of the top and urn base when the top is in open position.

Fig. 3 is an enlarged plan view of a portion of the upper end of the stove showing the points of pivotal engagement of the stove top and urn base with the stove.

Fig. 4 is a sectional view showing the pivotal connection of the stove top with the stove.

Fig. 5 is a sectional view showing the pivotal connection of the urn base with the stove.

Fig. 6 is a sectional view on the line 6—6 of Fig. 2.

The upper end frame 1 is for the most part of conventional construction and may be of oval form, as shown, or of other shape. This frame 1 is modified from usual construction by providing near one end means whereby the stove top and the urn base may obtain independent pivotal connection therewith. A flat portion 2 forms an integral part of the frame 1 in a plane generally below the upper surface of the frame 1. Around the inner edge of the flat portion 2 the frame 1 includes

a part 3. The depressed portion 2 is formed with a pivot hole 4 with which the outer edge of the part 3 is concentric and a slot 5 is formed through the part 2 concentric with the hole 4.

The stove top 6 is in the form of a plate of sufficient size to close the opening to the frame 1 and is provided with a central opening therethrough normally closed by a removable lid 7. This plate 6 has on its under side near one end a flange 8 arranged to seat upon the part 2 of the frame and to cooperate with a hinge device to support the plate 6 when said plate is in open position. The top plate 6 also has a pivot lug 9 engaging in the hole 4. An

angular projection 10 extends from the top plate 6 through the slot 5 and engages under the adjacent portion of the top plate. Thus, it will be seen that the top plate 6 may be turned about its pivot to open or to closed positions and that when in open position the pivotal connection with the frame 1 supports the top plate in approximately the same plane which it occupies when in closed position.

The top plate is formed along its outer edge with a depending flange 11 which, in closed position, is adjacent to a flange 12 on the frame 1. The top plate is releasably held in closed position by a lug 13 rising from the frame 1 a slight distance from the flange 12 so that the flange 11 of the top plate 6 may engage between the latch lug 13 and the flange 12 when the top plate is closed. In closed position the inner edge of the top plate 6 abuts against a raised portion 14 of the frame 1.

The urn base 15 may be of any appropriate design and has near one end a depending projection 16 designed and arranged to engage in a groove 17 in the upper side of the top plate 6. Near its opposite end the urn base is provided with an angular hinge arm 18 which extends downwardly through a hole 19 in the raised portion 14 of the frame 1 and engages under said raised portion 14. Thus, the urn base obtains pivotal engagement with the stove top frame eccentrically of the pivotal engagement of the top plate 6 with the stove top frame.

Assuming that the top plate 6 is in closed position and the urn base 15 is in position in which the projection 16 engages in the groove 17 and both the top plate 6 and the urn base 15 have pivotal engagement with the top frame of the stove, as described, it will

be understood that the top plate 6 may be moved to open position by engaging a handle 20 and swinging the top plate laterally about its pivot. This will also swing the urn base 5 laterally about its pivot 18 during which movement the projection 16 maintains engagement in the groove 17, thus requiring the urn base to move with the top plate. Or, the urn base 15 may be moved to open position 10 independently of the top plate 6 by slightly raising the free end of the urn base to disengage the projection 16 from the groove 17 and then turning the urn base laterally. This will afford access to the lid 7 while the top 15 plate 6 remains closed.

Preferably, the urn base is of such dimensions that it will cover a part of the raised portion 14 of the frame 1 when the parts are in closed position. However, the overlying 20 portion of the urn base is preferably above and out of contact with the frame part 14, being so supported by the projection 16 and other projections 21 on the urn base bearing upon the upper surface of the top plate 6. 25 An abutment 22 for the rear edge of the urn base may be provided upon the frame part 14, as desired.

From the foregoing the advantages and the benefits of my invention must be apparent, 30 as well as the fact that it obtains all its objects in a very convenient manner. I contemplate such variations as may be within the scope of equivalent limits.

I claim:

35 1. The combination with a stove top frame, of a top plate pivoted thereto for horizontal swinging movements, an urn base pivoted to said frame at a distance from the pivotal connection of said top plate with said frame for horizontal swinging movements, and means for operating the urn base by the top plate.

40 2. The combination with a top frame of a stove, of a top plate pivoted to said frame for horizontal swinging movement, an urn base pivoted to said top frame at a distance from the pivotal connection of the top plate with said frame, and a releasable connection between said urn base and said top plate 45 whereby said urn base will be swung laterally with said top plate.

50 3. The combination with a top frame of a stove, of a top plate pivoted to said frame for horizontal swinging movement, an urn base pivoted to said top frame at a distance 55 from the pivotal connection of the top plate

with said frame, and a releasable connection between said urn base and said top plate whereby said urn base will be swung laterally with said top plate and permitting said urn base to be swung laterally while said top plate remains stationary.

4. The combination with a stove top frame, of a top plate pivoted to said frame for horizontal swinging movements, an urn base 60 pivoted to said top frame above the plane of the pivotal engagement of the top plate with said frame for horizontal swinging movements, a handle for swinging said top plate horizontally, and means holding said 65 urn base in connection with said top plate.

5. The combination with a stove top frame, of a top plate for opening and closing said frame, an urn base upon said top plate, and separate pivots uniting said top plate and 70 said urn base with said top frame.

6. The combination with a stove top frame, of a top plate for opening and closing said frame, an urn base upon said top plate, separate pivots uniting said top plate and said 75 urn base with said top frame, means for swinging said top plate horizontally, and means for swinging said urn base horizontally by said top plate.

7. The combination with a stove top frame, 80 of a top plate for opening and closing said frame, means for releasably holding said plate in closed position, an urn base supported in part by said top plate, means pivoting connecting said top plate and said 85 urn base with said top frame, and a sliding connection between said top plate and said urn base for operating said urn base by said top plate.

8. The combination with a stove top frame, 90 of a top plate for opening and closing said frame, an urn base, means pivoting said top plate to said top frame for laterally swinging movements, and means pivoting said urn base to said top frame for lateral swinging 95 movements with said top plate or independently of said top plate, as desired.

9. The combination with a stove top frame, 100 of a top plate for opening and closing said frame, an urn base, means pivoting said top plate to said top frame for lateral swinging movements, means pivoting said urn base to said top frame for lateral swinging movements with said top plate or independently 105 of said top plate, as desired, and means for 110 operating said urn base by said top plate.

MAX R. LEHMAN.
